FIG. 1.

FIG. 2.

FIG. 3.

INVENTOR.

BY *Hugh W. Sanford*
Cyrus Keltz

ATTORNEY.

UNITED STATES PATENT OFFICE.

HUGH W. SANFORD, OF KNOXVILLE, TENNESSEE.

WHEEL.

1,420,221.

Specification of Letters Patent. Patented June 20, 1922.

Application filed October 22, 1920. Serial No. 418,729.

To all whom it may concern:

Be it known that I, HUGH W. SANFORD, a citizen of the United States, residing at Knoxville, in the county of Knox and State 5 of Tennessee, have invented a new and useful Improvement in Wheels, of which the following is a specification, reference being had to the accompanying drawing.

My invention relates generally to wheels 10 and it is especially applicable to mine cars and similar cars in which the axles are secured to the car body while the wheels are secured rotatably around the ends of the axles. The object of this invention is to 15 provide a wheel which will have as little end friction as possible and in which all the wear will be taken on the removable parts rather than on the wheel casting itself. Another object is to provide a wheel in 20 which there is an end cap which can be removed when necessary and which will at the same time stay tight and is not clumsy or will not project too far beyond the hub of the wheel. The invention consists in the 25 construction and arrangement of parts hereinafter more particularly described and then definitely claimed.

In the accompanying drawings:

Figure 1 is a vertical central section of 30 a journal having my wheel and bearing applied thereto.

Figure 2 is an end elevation of the hub of the wheel.

Figure 3 is an elevation of a non-rotatable 35 disk.

Referring now to the details of the drawings by numerals: 1 designates the axle which may be supported in any desirable way, preferably by a pedestal box 2 which 40 may be of the shape shown in Figure 1. The wheel 3 is provided with a hub 4 which is open at one end and may, if desired, be provided with an inwardly projecting flange 5 at its inner end, which flange is provided 45 with an aperture through which the journal projects as clearly shown in the drawing. The hub is preferably provided with an inner wearing member 7 which takes the

wear and prevents the wheel itself from being worn. Interposed between this wearing member 7 and the journal or axle 1 are a series of anti-friction rollers 8 provided with journals or gudgeons 9 at each end thereof. When the inwardly projecting flange 5 of the hub is employed, it 55 may, if desired, be provided with an annular projection 10 which projects from the flange 5 just about as far as the journals or gudgeons 9 project from the rollers 8. The outer end of the hub is formed preferably 60 as shown in Figure 2 and as there shown it is provided with, in the form shown in the drawings, three projecting members 12 each of which has a threaded aperture 14 for the reception of a screw as that shown 65 at 16 in Figure 1. Just to the rear of one of the threaded openings 14 is a cored hole 18 (see Figure 2) into which is fitted a pin 20, this pin being adapted to fit into a recess 21 in a washer 22 which is arranged 70 to fit over the free end of the journal 1 as illustrated in Figure 2, the purpose of the pin 20 being to prevent this washer from rotating. It will be obvious that other means may be used to prevent such rotation. 75 The washer 22 is provided with openings 24 through which oil may pass into the bearing proper. Around the journal 1 and between the heavy washer 22 and the ends of the anti-friction rollers 8 is a washer 26, 80 preferably of steel, which is designed to hold the rollers 8 in place whenever the wheel and the rollers are removed from the axle; the washer 22 being held by hand against the wheel hub so that it will be impossible for the rollers 8 to drop out, the washer 26 and the annular projection on the ring 10 holding the rollers in position leaving a space equal to the diameter of the axle 1. Around the end of the journal, outside of the heavy non-rotatable washer 22 are two additional washers 28 85 and 30, the first of which may be of compressed fibre if preferred, the washer 28 being free to move and the washer 30 being 90 immovable as will be explained. The end

of the journal is provided with an opening 32 to receive a locking pin 34 and the aforesaid non-rotatable washer 30 has its ends cut so they may be bent to embrace the ends 5 of the pin 34 as shown in Figure 2. The entire outer end of the journal is protected by a cap 40 which is designed to receive the end thrust from the axle 1 and which may be of any desired construction 10 but preferably of the form shown in the drawings. As illustrated it is provided with an annular flange 36 which is adapted to fit within the three projections 12 formed on the end of the hub shown in Figure 15 2. The outer surface of the flange of this cap is formed on an angle as shown at 44 so that when it is placed in position and the screws 16 screwed home through the openings 14, the angular ends of the screws 20 will wedge against the angular portions 44 of the flange of the cap 40 and thereby firmly lock the same against the heavy washer 22 to completely seal the end of the bearing. A wire locking device or a 25 cotter, as 46, may be used to prevent the screws 16 from vibrating loose. The cap 40 is further provided with an oil arrangement as that shown at 50 in Figure 1 which may be of the ordinary kind having a 30 spring valve. This oiling device is so arranged that it can be oiled in any position of the wheel since it comes out radially from the hub with a right angular bend as illustrated in the drawings. In the form 35 shown it is practically out of the way and protected by the projections against blows from objects along the track, and at the same time, if the cap 40 should become loose, the oiling device would turn with the cap 40 until it contacts with one of the projecting members 12, when the cap would be prevented from further rotation. When it is desired to remove the wheel from the axle, the pin 34, if opposite one of the holes 45 14, may be driven out by a driving tool (not shown) which may go through one of the holes 14 and drive out the pin 34, the latter passing through the space between two of the projecting members 12. 50 If, instead of employing three projections 12, as shown, there should be an even number of projections, then the driving tool would pass through the hole 14 of one projection and drive the pin 34 through the 55 hole in the opposite projection.

From the foregoing and accompanying drawing, it will be seen that I have provided a wheel and bearing for the same which is provided with a cap as 40, which is securely held in place where it will be tight and cannot get loose and which will at the same time take a severe end thrust. At the same time a fine reservoir for lubricant is formed by the cap 40 as will be noted 60 from an inspection of the drawings. If, for

any reason, the cap 40 should become loose the end pressure will be taken on the end of the pedestal box, a washer 48 being provided at that point to take the wear.

It will be obvious that changes and modifications may be made without departing from the spirit of my invention, the scope of which is set forth by the appended claims.

What I claim as my invention is:

1. In a wheel, and in combination with an 75 axle, a hub rotatable on said axle, an outer cap covering the end of the axle, and wedging means movable in a plane to which the axle is perpendicular for impinging endwise upon and locking said cap to the end of 80 said hub.

2. In a wheel, and in combination with an 85 axle, a hub rotatable on said axle, an outer cap, and means penetrating the outer part of the hub radially impinging upon the outer face of the cap for locking the same on the end of the hub over the end of the axle, said cap taking the end thrust and forming a closure for the bearing and a reservoir for 90 a lubricant.

3. In a wheel, and in combination with an 95 axle, a hub rotatable with an axle and having a projection thereon, an outer cap, and a screw carried by said projection and wedging against said cap to hold the latter 100 against the hub, the cap taking the end thrust from the axle.

4. In a wheel, and in combination with an 105 axle, a hub rotatable with an axle, a removable outer cap, and washers receiving the part of the hub radially and being approximately flush with the outer face of the hub. 110

5. In a wheel, and in combination with an 115 axle, a hub rotatable with an axle, and having a plurality of projections thereon, an outer cap, and screws carried by said projections and wedging against said cap to hold the latter against the hub.

6. In a wheel, and in combination with an 120 axle, a hub rotatable on said axle, and having a plurality of projections thereon, an outer cap having an annular flange, and screws carried by said projections and co-acting with said flange to lock said cap against the hub.

7. In a wheel, and in combination with an 125 axle, a hub rotatable on said axle, and having a plurality of projections thereon, an outer cap having an annular flange with a slanting face, and screws carried by said projections and wedging against the slanting face of the flange on the cap to lock the latter against the hub.

8. In a wheel, the combination of a hub, an axle therefor, rollers around said axle, a 130

heavy non-rotatable wearing washer over said axle and bearing against the end of said hub, and a cap holding the washer against the end of the hub, and means acting radially to the axle to detachably secure the cap to the hub.

9. In a wheel, the combination of a hub, an axle therefor, rollers around said axle, a heavy non-rotatable wearing washer over said axle and bearing against the end of said hub, a device as the pin 34 for holding said hub on the axle, and a wearing washer interposed between said device and the aforesaid non-rotatable washer, a cap extending over the end of the axle, and means acting radially to the axle to detachably secure the cap to the hub.

10. In a wheel, the combination of a hub, an axle therefor, rollers around said axle, a heavy non-rotatable wearing washer over said axle and bearing against the end of said hub, and washers on opposite sides of said non-rotatable washer, a cap extending over the end of the axle, and means acting radially to the axle to detachably secure the cap to the hub.

11. In a wheel, the combination of a hub, an axle therefor, a heavy non-rotatable wearing washer over said axle and bearing against the end of said hub, a pin for holding said hub on said axle, and a non-rotatable washer alongside of said pin to prevent wear on said pin, a cap extending over the end of the axle, and means acting radially to the axle to detachably secure the cap to the hub.

12. In a wheel, the combination of a hub, an axle therefor, rollers around said axle, a heavy non-rotatable wearing washer over said axle and bearing against the end of said hub, a pin for holding said hub on said axle, and two washers between said non-rotatable washer and said pin, one of which is fixed to the pin to prevent wear thereon, a cap extending over the end of the axle, and means acting radially to the axle to detachably secure the cap to the hub.

13. In a wheel, the combination of a hub, an axle, a non-rotatable wearing plate, means for preventing rotation of said plate, and a cap for covering the end of the axle, and rotatable means for impinging endwise upon the outer face of the cap to detachably secure the cap.

55 14. In a wheel, the combination of a hub having a plurality of projections on the end thereof, an axle, a cap covering said axle and locked to said hub, and an oiling device projecting from said cap between the aforesaid projections whereby said oiling device is protected by said projections and said oiling device may bear against one of said projections and limit the turning of said cap when the latter becomes loosened.

65 15. In a wheel, the combination of a hub

having a plurality of projections on the end thereof, an axle, a pin passing through the axle for locking the wheel on the axle, said projections each having an opening therein by which the pin may be removed from said axle, and a cap detachably secured to the hub and covering the pin and the end of the axle.

16. In a wheel, and in combination with an axle, a hub rotatable on said axle, an outer cap covering the end of the axle, and wedging screws seated in the hub and movable in a plane to which the axle is perpendicular for locking said cap to the end of said hub.

17. In a wheel, and in combination with an axle, a hub rotatable on said axle, an outer cap covering the end of the axle, wedging screws seated in the hub and movable in a plane to which the axle is perpendicular for locking said cap to the end of said hub, and a locking device applied to said screws.

18. In a wheel, and in combination with an axle, a hub rotatable on said axle, a pin extending transversely through the axle, holes in the hub in the plane of said pin and radial to the axle, so that one of said holes may be brought into alignment with said pin and then permit the passing of said pin through said hole or the passing of a tool through said hole to drive said pin endwise away from said hole, a wedging screw adapted to be seated in said hole, and an outer cap covering the end of the axle and engaged by said wedging screw.

19. In a wheel, and in combination with an axle, a pin seated removably and transversely in said axle, a hub rotatable on said axle and extending into the plane of said pin and having openings in said plane and at opposite sides of said axle and adapted to be brought into alignment with said pin, an outer cap covering the end of the axle, and wedging screws placed in a portion of said openings and engaging the edge of said cap to secure the latter to the hub, said pin being removable through one of said openings when that opening and another have been, by the turning of the hub, brought into alignment with said pin.

20. In a wheel, the combination of a hub having a plurality of projections on the end thereof, an axle within the hub, a cap covering said axle and locked to said hub, and an oiling device threaded into said cap radial to said axle between two of said projections on the hub, whereby said oiling device is protected by said projections and said oiling device may bear against one of said projections and limit the turning of said cap when the latter becomes loosened.

21. In a wheel, the combination of a hub having a plurality of projections on the end thereof, an axle within the hub, a cap cover-

ing said axle and locked to said hub, and an oiling device threaded into said cap radially to said axle between two of said projections on the hub, whereby said oiling device is protected by said projections and said oiling device may bear against one of said projections and limit the turning of said cap when

the latter becomes loosened, and the outer end of said oiling device being turned parallel to the axle.

In testimony whereof I have signed my name this 20th day of October, in the year one thousand nine hundred and twenty.

HUGH W. SANFORD,
